GRINDER FOR HARD CELLULAR PLASTIC OR THE LIKE

Archie F. Keys, 300 W. 7th St., and Thomas F. Ormsby,
2908 W. 11th St., both of Plainview, Tex. 79072
Filed Aug. 4, 1964, Ser. No. 387,424
2 Claims, (Cl. 241—88)

This invention relates to an apparatus for grinding pieces of hard cellular plastics, which is usually known in the trade as styrofoam or the like, so as to disintegrate this into a material which is slightly coarser than normal sawdust, so the disintegrated material may be used in flower pots, for packing, and the like.

This invention is particularly adaptable for use in shops which utilize styrofoam and where scraps are left which are not sufficiently large for the original use. The present apparatus is especially adaptable for use in flower shops, which use styrofoam on which to create floral designs, as such shops usually have a considerable quantity of styrofoam which may be readily disintegrated into usable material, as set out above.

The present invention is so constructed that it may be readily clamped to a bench, table, shelf, or the like, to perform a grinding action on such material as needed and then the device can be removed and stored so as to be out of the way.

The present device may be powered by a small gear reduction motor, such as a hand drill or the like. Powering the present device with a hand drill makes it possible to hold the cost to a minimum, as the hand drill can double for the drive motor on the present device and for normal daily use as a hand drill.

The device is so constructed that it may be readily dismantled for repair and replacement of parts, or for the sharpening of the saw or grater blade, should such sharpening become necessary.

Furthermore, the device is constructed with a relatively small intake opening, and with a relatively deep throat, so as to preclude the possibility of getting a hand into the hopper of the device, thereby practically eliminating a portion of the hand becoming mangled by the saw teeth. Furthermore, a protective elastomer door is secured on the device which will permit the entrance of styrofoam blocks or the like into the hopper of the device. However, upon trying to insert the hand through such opening, the cover gives ample warning of the existence of the opening.

An object of this invention is to provide a disintegrating machine which may be readily set up in a small space and which may be operated without the necessity of having a large mill to grind the styrofoam into sawdust-like material.

Another object of the invention is to provide a grinding mill which will readily grind up scrap blocks of styrofoam into sawdust-like material for use in flower pots, for packing and the like.

Still another object of the invention is to provide a mill for grinding styrofoam into sawdust-like material, which mill is small, compact and which may be readily driven by a small drill motor.

Still another object of the invention is to provide a styrofoam grinder or grater which utilizes a cylindrical drum, having spirally arranged saw teeth thereon to disintegrate styrofoam into relatively small bits, similar to sawdust, or the like.

Another object of the invention is to provide a styrofoam grinder or the like which has a cushioned lining therein to minimize chattering noise during the grinding operation.

Another object of the invention is to provide a styro-

2

foam grinding mill that is simple in construction, low in the cost of manufacture, easy to assemble and disassemble, and relatively trouble free in operation.

With these objects in mind and others which will become manifest as the description proceeds, reference is to be had to the accompanying drawings in which like reference characteristics designate like parts in the several views thereof, in which:

FIG. 1 is a perspective view of the device, showing a sack or other container therebelow, in dashed outline;

FIG. 2 is a sectional view taken on line 2—2 of FIG. 3, with parts broken away and with parts shown in elevation to bring out the details of construction;

FIG. 3 is a sectional view taken on line 3—3 of FIG. 2, looking in the direction indicated by the arrows, portions thereof being shown in dashed outline, to indicate the feeding of scrap styrofoam blocks thereto, the elastomer safety door being shown in depressed condition in dashed outline, and also showing a receptacle, such as a sack, attached to the lower end of the styrofoam mill by a rubber band or the like; and

FIG. 4 is a fragmentary view of the open, grater-like material of expanded metal for use in the bottom of the device.

With more specific reference to the drawings, the numeral 1 designates generally a styrofoam grinding mill showing a gear reduction motor 2 attached thereto for operation thereof, which, in the present instance, is shown to be a hand drill. The numeral 4 designates the side plates on which is secured C-clamp members 6 which are secured to a side thereof, as by welding, to enable the grinding mill 1 to be attached to a shelf, table, bench or the like, as indicated at 8.

A front portion 10 is formed, as will best be evident in FIGS. 1 and 3, to be positioned between the forward portion of the side plates 4 and a back portion, as indicated at 12, is positioned intermediate the side plates 4 on the rear side thereof.

Each side plate 4 is apertured at the top, on each side thereof, and at the bottom, which apertures receive bolts or studs 13 therethrough to bindingly engage the side plates 4 in secure relation to the front portion 10 and to the back portion 12. The front portion 10 has a re-entrant portion 9, which forms a guideway for styrofoam blocks 26. The lower end of the front portion 10 has an upwardly curved portion 11, which is adapted to surround front boss 11a which is impressed into each side of each side plate near the lower end thereof. The back portion 12 has a downwardly and inwardly re-entrant portion 12a so as to form a backing for elastomer liner portion 32. The back portion 12 extends downward into close proximity to the points of teeth 24, with an offset portion to allow an end of the semi-cylindrical, expanded metal bottom to extend upward between the back portion 12 and the rubber liner portion 32, so that teeth 33 of the liner portion will come into very close proximity with teeth 24, when the cylinder 18 is rotated. The liner portion 32 extends upward over the uppermost bolt 13 with a portion 35 extending downward to at least partially close the upper throat 25. The back portion 12 has an upwardly curved re-entrant portion 12b on the lower end thereof to surround opposed bosses 11a on the rear of side plates 4.

Each side plate 4 has a bearing sleeve 14 therein, near the lower end thereof, to receive a shaft 16 to which drum 18 is secured for rotation therewith. A saw or grater blade 20 has a flat portion turned outward at a substantially right angle to the teeth 24 thereof, which flat portion is perforate near each end to receive screws 22 therethrough to attach the saw or grater blade 20 to the cylinder 18 in a spirally arranged position, so that the

teeth 24 will be upstanding therefrom to engage the styrofoam blocks 26, so upon rotation of cylinder 18 the styrofoam blocks will be disintegrated into sawdust-like material, upon rotation of the cylinder 18 by the motor 2. Each side plate 4 has a concave, annular ring 28 surrounding bearings 14 and spaced therefrom so as to be co-axial with the bearings 14. This annular, concave ring 28 is adapted to receive an arcuate, perforate, semi-cylindrical member 30, which is preferably made of non-flattened, expanded metal, with a portion of the metal 5 having slots formed therein, which are arranged with the length of the slots in parallel, aligned relation with the axis of shaft 16, with the inner arcuate surface of the semi-cylindrical member 30 being spaced in close proximity to the points of teeth 24 so that any pieces of styrofoam which finds its way downward between the elastomer back 32 and the cylinder 18 will be sawed or grated by saw teeth 24 until the disintegrated material will fall through the openings 34 in semi-cylindrical, expanded metal member 30, thence downward through an open 10 end 36 into a sack or container 38 which is secured to the lower end of side plates 4 by a rubber band 40, or the like. Each side plate 4 has an indentation 42 on each side thereof at the lower end, as indicated at 42, so as to form a recess to enable rubber band 40 to bind the sack 15 20 25 38 or the other container thereto.

Operation

With the device assembled as shown in FIG. 1, a motor, 30 such as drill 2, is connected to the outwardly extending reduced portion 17 of shaft 16, as by a drill chuck 3, and the device is rotated in the direction indicated by the arrow in FIG. 3. Styrofoam blocks, of such sizes and dimensions as will pass through opening 25, are fed downward so as to depress elastomer door 35, with the styrofoam blocks 26 engaging the rotating cylindrical drum 18, whereupon the teeth 24 will grind or grate the styrofoam into small particles, which will be carried downward between back 12 and cylinder 18, outward through 35 40 45 the holes 34 in semi-cylindrical, expanded metal member 30, with the disintegrated styrofoam or the like being discharged out through opening 36 in the bottom of the housing formed by sides 4 and the front and back portions 10 and 12, respectively, which disintegrated material will be directed into a sack or receptacle 38.

When sufficient material has been grated from scrap, hard styrofoam blocks, the motor 2 may be disconnected from the reduced portion of shaft 17 by loosening the chuck 3, and the mill apparatus 1 may be unclamped from the table 8 by loosening C-clamp 6, so the device may be conveniently stored.

Having thus clearly shown and described the invention, what is claimed as new and is desired to be secured by Letters Patent is:

1. In a grinding mill for disintegrating hard, cellular, plastic blocks and the like, comprising;
- (a) a housing including
    - (1) side plates,
    - (2) a front plate, and
    - (3) a back plate,
  - (b) said housing having an opening formed in the upper and lower ends thereof, respectively,

- (c) a cylindrical member journaled intermediate the ends of said housing,
  - (d) a spirally arranged toothed member attached to said cylindrical member for rotation therewith,
  - (e) a shaft extending outward from an end of said cylindrical member for rotation of said cylindrical member therewith,
  - (1) said back plate having the inner surface thereof covered with an elastomer material, which material extends downward at least to a horizontal plane passing through the axis of said shaft,
  - (2) a perforate, arcuate, semi-cylindrical member, having an end thereof extending upward beneath the lower end of said elastomer covering material on said inner face of said back portion of said housing,
  - (3) said back plate has spaced apart, outwardly extending elastomer bosses thereon, which bosses extend into close proximity to the teeth of said toothed member, and
  - (f) power means adapted to be connected in driving relation with said shaft.
2. A grinding mill for disintegration of hard, cellular plastic blocks, and the like, comprising;
- (a) a housing including
    - (1) side plates,
    - (2) a front plate, and
    - (3) a back plate,
  - (b) said housing having an opening formed in the lower ends thereof, respectively,
  - (c) a cylindrical member journaled intermediate the ends of said housing,
  - (d) a spirally arranged toothed member attached to said cylindrical member for rotation therewith,
  - (e) a shaft extending outward from an end of said cylindrical member for rotation of said cylindrical member therewith,
  - (1) said back plate having the inner surface thereof covered with an elastomer material, which elastomer material, extends downwardly and inwardly across at least a portion of the opening formed in the upper end of said housing,
  - (2) a perforate, arcuate, semi-cylindrical member, having an end thereof extending upward beneath the lower end of said elastomer covering material on said inner face of said back portion of said housing, and
  - (f) power drive means adapted to be connected in driving relation with said shaft.
